UNITED STATES PATENT OFFICE

159,706

PAPER MONEY CLIP

Elizabeth L. Wilcox, Chicago, Ill.

Application December 31, 1949, Serial No. 6,944

Term of patent 3½ years

(Cl. D74—2)

To all whom it may concern:

Be it known that I, Elizabeth L. Wilcox, a citizen of the United States, residing at Chicago, State of Illinois, have invented a new, original, and ornamental Design for a Paper Money Clip, of which the following is a specification, reference being had to the accompanying drawing, forming a part hereof.

Fig. 1 is a front elevational view of a paper money clip showing my new design.

Fig. 2 is a rear elevational view thereof.

Fig. 3 is an end perspective view thereof.

I claim:

The ornamental design for a paper money clip, as shown.

ELIZABETH L. WILCOX.
